TABULATING MECHANISM FOR ACCOUNT-
ING MACHINES

Raymond A. Christian, Dayton, Ohio, assignor to
The National Cash Register Company, Dayton,
Ohio, a corporation of Maryland

Original application February 2, 1932, Serial No.
584,438. Divided and this application October
28, 1933, Serial No. 695,662

4 Claims. (Cl. 197—176)

This invention relates to accounting or book-keeping machines and the like but more particularly to machines of this type having a traveling carriage such as are set out and described in 5 Letters Patent of the United States Nos. 1,197,276 and 1,197,278 issued September 5, 1916 to Hal-colm Ellis, and Patent No. 1,203,863 issued November 7, 1916 to Halcolm Ellis; and is a division 10 of the application for United States Letters Patent of Raymond A. Christian Serial Number 584,438 filed February 2, 1932.

One object of this invention is to provide novel means for locking the machine releasing mechanism when the traveling carriage is being tabulated manually.

Another and more specific object of this invention is to provide novel means intermediate the tabulating means and the machine releasing means for blocking movement of the latter when 20 the tabulating stop means is disabled.

With these and incidental objects in view the invention includes certain novel features of construction and combinations of parts the essential elements of which are set forth in appended 25 claims and a preferred form of embodiment which is hereinafter described with reference to the drawings which accompany and form a part of this specification.

Of said drawings:

30 Fig. 1 is a detail view of the mechanism for locking the machine against release during manual tabulation of the traveling carriage.

Fig. 2 is a view showing in detail the manual tabulating mechanism.

35 Fig. 3 is a perspective view of a portion of the machine case, traveling carriage frame, and platen (all being shown in dot and dash lines) and a portion of the manual tabulating mechanism showing the relative position thereof with regard 40 to the traveling carriage frame.

Detailed description

The present invention is incorporated in a machine of the well known Ellis type having a 45 traveling carriage and a tabulating mechanism such as shown in the previously mentioned Ellis patents. The usual platen roll 44 is journaled in a traveling carriage frame 45 slidably mounted on a machine case 46 which encloses the machine mechanism, and is in turn supported by a machine base (not shown).

Convenient means for releasing the traveling carriage frame 45 for tabulation have been supplied in the machine of the present invention, 55 and will now be described in detail.

Referring to Figs. 2 and 3, a touch bar 91 is secured to a tabulating release bar 92 slidably mounted on a tabulating stop bar 93 (shown by dot and dash lines in Fig. 3) by means of a plurality of diagonal slots embracing studs 94 secured in said stop bar 93 which is in turn secured to the traveling carriage frame 45. The lower edge of the release bar 92 is adapted to co-operate with a tabulating plunger 95 mounted to slide vertically in a tabulating frame (not shown). The upper end of the plunger 95 is adapted to co-operate with a plurality of the usual stops 96, only one here shown (Fig. 3), to enable the traveling carriage frame 45 to be moved step by step from right to left. The plunger 95 (Fig. 2) has a hole to receive a stud 97 carried by a plunger lever 98 pivoted to the tabulating frame. The right end of the lever 98 is arranged to co-operate with a slot 99 in an automatic tabulating lever 100 (Figs. 1 and 2) which is 20 pivoted to the right machine frame (not shown).

Pivoted to a stud 101 in the automatic tabulating lever 100 (Fig. 1) is a link 102 having a slot through which extends a stud 103 in rocking lever 104 pivoted to the right machine frame. 25 A spring 105 is stretched between the studs 101 and 103 to form a flexible connection between the levers 100 and 104. The lever 104 has a notch 106 adapted to co-operate with a square stud 107 in a starting lever 108 pivoted at 109 30 to right machine frame (not shown). One end of a starting bar 110 is pivoted to the lever 108 so that depression of the starting bar 110 rocks the lever 108 counter clockwise to release the machine for operation in the well known manner. 35

Depression of the touch bar 91 (Figs. 2 and 3) moves the plunger 95 downwardly out of the path of tabulating stops 96 which allows the traveling carriage 45 to be moved freely in either direction. The downward movement of the plunger 95 rocks 40 the levers 98, 100 and 104 clockwise causing the latch 106 to move into the path of the stud 107 to thus prevent depression of the starting bar 110 as long as the touch bar 91 remains depressed.

Release of the machine for operation causes the 45 stud 107 (Fig. 1) to move upwardly to a position above the notch 106 thus blocking any movement of the lever 104. However, due to the slot in the link 102 the automatic tabulating lever 100 is permitted to function. The description, operation, and also illustration of automatic tabulation may be found in a United States Letters Patent granted to F. W. Bernau No. 1,731,701 dated October 15, 1929.

The slot in the link 102 also prevents any bind- 55

ing or injury to the part should the operator depress the touch bar 94 after the machine has been released by depression of the motor bar 110.

While the form of mechanism herein shown and described is admirably adapted to fulfill the objects primarily stated it is to be understood that it is not intended to confine the invention to the one form of embodiment herein disclosed for it is susceptible of embodiment in various forms all coming within the scope of the claims which follow.

What is claimed is:

1. In a machine of the class described, having a traveling carriage and means for releasing the machine for operation; the combination of tabulating means for the traveling carriage; means for disabling the tabulating means; and means operated by the tabulating means when disabled for locking the machine releasing means.
2. In a machine of the class described the combination of means for releasing the machine for operation; a traveling carriage; tabulating stop means therefor; means for disabling the tabulating stop means; and means connected to the tabulating stop means for blocking the movement

of the machine releasing means when said tabulating stop means is disabled.

3. In a machine of the class described the combination of machine releasing means; a traveling carriage; tabulating stop means therefor; manual means for disabling the tabulating stop means; means for operating the tabulating stop means; a link; a spring; and a pivoted member connected by the said link and spring to the tabulating stop operating means to block the movement of the machine releasing means when the tabulating stop means is disabled.

4. In a machine of the class described, the combination of means for releasing the machine for operation; a traveling carriage; tabulating stop means therefor; means for disabling the tabulating means; and a device intermediate the machine releasing means and the tabulating stop means adapted to be operated by the latter to move said device into the path of movement of said machine releasing means to prevent operation thereof when the tabulating stop means is disabled.
